UNITED STATES PATENT OFFICE.

DOUGLAS MYRICK ALLEN, OF LAKE CHARLES, LOUISIANA, ASSIGNOR OF ONE-HALF
TO DALLAS GROSS, OF LAKE CHARLES, LOUISIANA.

ADAPTER SWITCH FOR CEILING FANS.

1,404,080.

Specification of Letters Patent. Patented Jan. 17, 1922.

Application filed November 6, 1920. Serial No. 422,233.

To all whom it may concern:

Be it known that I, DOUGLAS M. ALLEN, a citizen of the United States, residing at Lake Charles, in the parish of Calcasieu and 5 State of Louisiana, have invented certain new and useful Improvements in Adapter Switches for Ceiling Fans; and I do hereby declare the following to be a full, clear, and exact description of the invention, such as 10 will enable others skilled in the art to which it appertains to make and use the same.

The present invention relates to adapted switches for ceiling fans and the like, and has for an object to provide a replacement 15 unit to supersede the usual turn button switch by which ceiling fans are at the present time controlled in order that the fan may be stopped, started or driven at any required speed by mechanism that may be controlled 20 conveniently from the floor without the necessity of mounting a ladder or using a long instrument to turn the button switch.

Another object of the invention resides in providing an improved switch actuating 25 mechanism for carrying out the above described features, which is simple and inexpensive in construction, and extremely effective for the purpose stated.

With the foregoing and other objects in 30 view, the invention will be more fully described hereinafter, and will be more particularly pointed out in the claims appended hereto.

In the drawings, wherein like symbols re- 35 fer to like or corresponding parts throughout the several views,

Fig. 1 is an enlarged view in elevation of the interior parts of the switch operating mechanism;

Fig. 2 is a horizontal sectional view taken 40 on the line 2-2 in Fig. 1;

Fig. 3 is a similar view taken on the line 3-3 in Fig. 1;

Fig. 4 is a plan view of the drum;

Fig. 5 is a partial elevation and sectional view of parts of the drum and ratchet showing the connection with the fan switch; and

Fig. 6 is a fragmentary diagrammatic 50 view showing the fan and switch operating mechanism applied thereto.

Referring more particularly to the drawings, 1 designates the fan switch box containing the usual switch which is at the present time customarily actuated by a turn 55 button projecting through a cover which

encloses one end of the box 1. A threaded shaft 2 projects from this end of the box and receives the turn button. The turn button and cover are removed and the apparatus constructed according to the present invention is connected to the shaft 2 to actuate the switch mechanism within the box 1 in precisely the same manner as it is operated by the turn button.

The apparatus consists of a ratchet wheel 65 3 screwed onto the shaft 2 and cooperating with a pawl 4 pivoted at 5 within a drum 6 carried on the upper end of a post 7. The post 7 is mounted in the central portion of a horizontal bar 8 extending between the 70 lower ends of a pair of arms 9 and 10. These arms have their upper ends inturned as indicated at 11 and 12 and perforated to cooperate with fastening means by which the device as a unit is attached to the fan 75 structure. A coil spring 13 is wound about the post 7 and has one end 14 engaged with the horizontal bar 8. The other end 15 of the spring projects in the same direction with the axis of the convolutions of the 80 spring and is adapted to fit in one of a series of perforations 16 made in the lower face of the drum 6 as shown in Fig. 4. These perforations 16 are for the purpose of adjusting the tension of the spring.

A flat spring 17 lies within the inner portion of the drum 6 having one end secured as by a screw 18 to the drum, while its other end engages the pawl 4 and yieldingly presses the same into the teeth of the ratchet 90 3. A cord 19 is wound about the grooved drum 6 and has one end engaged in a selected aperture of a series of apertures 20 made in the periphery of the drum.

A set screw 21 cooperates with the ap- 95 tures 20 and is threaded through the side of the drum in order to bind the end of the rope or cord 19 in the aperture selected. The lower peripheral edge of the drum 6 is cut away as indicated at 22 in Fig. 4 and 100 provides a pair of stop shoulders 23 and 24 for limiting the movement of the drum in opposite directions.

The cord 19 passes from the drum onto a grooved pulley 25 mounted in webs or flanges 105 26 and 27 projecting from the arm 9. These webs or flanges 26 and 27 project diagonally to the plane passing through the two arms 9 and 10 in order to present the pulley 25 at the proper angle to receive the cord 19 110

and to guide it downwardly through the space between the curved portions of the arm 9 to and through a guide 28 made at the base of the arm 9 where it joins with the horizontal bar 8. The cord or rope depends to a suitable distance from which it may be readily grasped by the operator standing upon the floor beneath the fan.

In operation the cord 19 is pulled downwardly thus serving to partially rotate the drum 6 in a clockwise direction as looked at in Fig. 2. This causes the pawl 4 to slip loosely over the teeth of the ratchet 3 and at the same time to wind the spring 13 to a potential condition capable of restoring the drum 6 in the opposite direction to the initial position when the cord 19 is released. During this counterclockwise movement of the drum 6 by virtue of the action of the spring 13 the pawl 4 will engage with an abrupt face of one of the ratchet teeth 3 and thus carry the ratchet with it so that through the threaded shaft 2 to which the ratchet is connected the switch mechanism 25 within the box 1 will be actuated. The cord is drawn more or less in accordance with the speed of the fan desired.

When the drum is moved in one direction the stop shoulder 23 will engage the flange 27 and prevent a further movement of said drum, while the stop 24 performs a similar function of striking the grooved pulley 25 on the drum being moved in a predetermined distance in the opposite direction.

It is obvious that various changes and modifications may be made in the details of construction and design of the above specifically described embodiment of this invention without departing from the spirit thereof, such changes and modifications being restricted only by the scope of the following claims.

What is claimed is:

1. In combination with a switch having an actuating shaft, a ratchet wheel secured to turn with the actuating shaft, a pawl engaging the ratchet wheel, a drum mounted co-axially with the actuating shaft and carrying said pawl, resilient means also carried by said drum for yieldingly urging the pawl against the teeth of the ratchet wheel, a post supporting said drum, a bar to which

the lower end of said post is secured, arms extending upwardly from the opposite ends of said bar forming a unitary support for the device, webs extending from one of said arms diagonally with respect to said drum, a pulley journaled in said webs and having its periphery arranged close to the lower side of the drum, said lower side of the drum being cut away at one portion to permit the periphery of the pulley to project thereinto, the opposite ends of the cut away portion of the drum forming stops to strike against said pulley, an operating cable engaging over said pulley and about said drum and being affixed to the latter, and resilient means extending about said post and engaging at one end with said drum and at the other end with said bar, substantially as described.

2. In combination with ceiling fan switch having substantially vertical actuating shaft formed with a reduced threaded lower end, a ratchet wheel threaded upon the projecting end of said shaft, a pawl engaging therewith, a drum extending beneath said ratchet wheel and co-axial with the actuating shaft, said drum pivotally carrying said pawl, yieldable means on the drum for urging the pawl into the teeth of the ratchet wheel, said drum provided with a grooved periphery having a portion of said lower side cut away and having stops at the opposite ends of the cut away portion, a post supporting said drum, a horizontal bar supporting said post, supporting arms extending upwardly from opposite ends of said bar, a coil spring wound about said post and having its ends engaged respectively with said bar and drum, said drum having a series of perforations adapted to adjustably engage the upper end of said spring, webs extending diagonally from one of said arms beneath the drum, a pulley journaled in said webs and having its edge adapted to enter the cut away portion of the drum and to engage the stops at the ends of the cut away portion, said drum having a number of openings in its periphery, and an operating cable wound about said pulley and drum and having one end selectively fitted in one of the openings, substantially as described.

DOUGLAS MYRICK ALLEN.
